SEAL

Charles M. Allen, Columbus, and Russell W. Dayton, Worthington, Ohio, assignors, by mesne assignments, to Battelle Development Corporation, Columbus, Ohio, a corporation of Delaware

Application May 25, 1950, Serial No. 164,222

7 Claims. (Cl. 286—9)

1

The present invention relates to improvements in shaft seals. More specifically, this invention relates to centrifugal fluid shaft seals embodying new and novel means for reducing turbulence and thereby increasing the pressure which the seal is able to withstand and for reducing the leakage pass or through the seal.

In U. S. patents to Richardson, 1,014,350, Masterson et al., 1,784,104, and Shaw et al., 2,447,034 are shown centrifugal fluid shaft seals of representative design with which this invention is generally concerned. Sealing is effected in these devices by fluid held between the vane or stator and the rotating trough or rotor. As the trough rotates the fluid is thrown outward and builds up a high pressure between the stator dipping into the fluid and the trough of the rotor owing to centrifugal force so that it is able to withstand considerable differences in pressure. The prior art has also shown that certain modifications are possible to enable the seal to be used in a vertical position or when the shaft is stationary. In such cases double rotors are generally employed which are driven independently of the shaft, and one of the cooperating vanes or stators is attached to the shaft and may rotate at any independent speed while the other is secured to the atmosphere or pressure chamber, wall, etc. One or more pockets or traps in the rotors or stators may also be provided to hold the fluid when the system is not operating in order to prevent its escape from the seal.

It has been found, however, that the maximum benefit in increased pressure and reduced leakage that might possibly be derived from such devices is not achieved due to what is apparently turbulence of the fluid caused by the rotating fluid in the rotor trough impinging against the sides of the vane or stator. Accordingly, it would be highly desirable to effect a substantial reduction in this turbulence to enable such seals to be used under conditions of increased pressure or differences in pressure and without appreciable leakage, and it is, therefore, an important object of this invention to provide a shaft seal having means to reduce the turbulence of the fluid under operating conditions.

It is another object of this invention to provide a centrifugal shaft seal with baffling to reduce the turbulence of the fluid and thereby enable the seal to be used under conditions of increased pressure with reduced leakage.

It is a further object of this invention to provide for a centrifugal fluid shaft seal, a rotor having in its trough continuous baffling charac-

2

terized by reducing the turbulence of the sealing fluid.

It is a still further object of this invention to provide the rotor of a centrifugal shaft seal with a plurality of equally spaced baffles therein defining pockets for holding a fluid and preventing turbulence thereof.

These and other objects and advantages of the present invention will become more apparent from the following detailed description and drawing, in which

Figure 1 is a partial vertical, sectional view of a rotor and stator of a representative centrifugal shaft seal with the fluid removed and containing the turbulence-reducing baffling of this invention, and

Figure 2 is a vertical, sectional view of the baffling to be inserted in the trough, and

Figure 3 is a fractional, sectional view of the device shown in Figure 1, showing the relationship of the baffle and the sealing fluid, and

Figure 4 is a fractional, sectional view along the line A—A of Figure 1 showing the pockets formed by the baffling, the arrows in the pockets showing the current direction of the fluid in the pockets when the rotor and its baffling are moving in the indicated direction, and

Figure 5 is a fractional, sectional view along the line C—C of Figure 1 showing the serpentine shape of the baffling, and

Figure 6 is a fractional, sectional view of a portion of the device of Figure 5 showing the disposition of the fluid relative to the baffling, and

Figure 7 is a fractional, sectional view similar to Figure 5 but showing a modification of the invention wherein a plurality of baffles are inserted around the outer portion of the trough of the rotor, and

Figure 8 is a partial vertical, sectional view of one of the inserts disclosed in Figure 7.

It has now been discovered that a substantial reduction in turbulence of shaft seals can be effected resulting in an increase in pressures obtainable with a reduction in leakage by securing baffling in the moving member of a shaft seal in close proximity to the vane or stator. The baffling creates a plurality of interconnected pockets for the sealing fluid in the trough of the rotor. As the fluid in the trough moves past the stator, eddy currents are created in the fluid in each pocket due to the drag on the fluid by the stator. The currents interfere at the fringes with the currents in the adjacent pockets since the common walls between the pockets are perforated or

50
55

interconnected. Thus, the turbulence and velocity of the sealing fluid is reduced, resulting in increased pressure and reduced leakage.

In general, as shown in the drawing, Figures 1 to 6, the annular rotor is designated as 1 and has dual fins 2-2 and sides or walls 3-3 defining internal annular chamber or trough 4. The rotor may be driven independently of shaft 5 by any means such as a belt or gearing or may be by suitable gearing connected to the shaft. Spaced about equidistant from the internal sides of the rotor and in the trough is annular member 6 which as a vane may be secured to the shaft and rotate at a speed relatively less than said rotor or as a stator may be fixably secured to concentric sleeve 7 which is spaced about said shaft and which is attached to wall 8 of a motor housing or atmosphere or vacuum chamber 9. Secured to the rotor in the outer end of the trough throughout its circumferential length is perforated or screen baffling 10 having a generally serpentine shape. While in Figure 5, the baffling 10 has been shown as having a generally serpentine shape with loops of rounded design, it will be understood that the loops can be of any shape, for example, square or triangular, without departing from the scope of the invention or the new and novel results obtained. The baffling is continuous about the annular, generally outer portion or periphery of the trough and has slot 11 extending for a portion of the distance from its free end or portion into which the vane freely extends.

In operation of the shaft seal, the mercury 12 which is used as a sealing fluid is thrown outward by centrifugal force when the rotor moves, and it lies in the outer portion of the trough formed by the walls of the rotor. Due to pressure differences between the outside atmosphere and the vacuum chamber, it occupies positions 13 and 14 of different height on either side of the peripheral portion 15 of the vane. As shown particularly in Figure 4, the baffling, walls of the rotor, and stator form a plurality of pockets for the mercury, the pockets being interconnected since the baffling is perforated. As the mercury carried by the rotor moves past the stator in the direction indicated by the arrows 16-16 frictional forces set up eddy currents, as shown by arrows 17-17, in the fluid in each pocket. These currents tend to meet and counteract each other by passage through the perforations of the baffling. In this manner the customary turbulence and velocity of the mercury is reduced and results in the obtainment of increased pressures and reduction in leakage during sealing operations. The baffling must be secured to the rotor and not to the vane or stator for otherwise the opposite effect would be obtained as a great increase in turbulence would result providing increased leakage and preventing the use of the seal under conditions of even small pressure differentials.

While many methods for inserting the baffling will suggest themselves readily to those skilled in the art, it has been found best to first form screening, made of about 12 gauge nickel wire, in a serpentine shape and weld it to the inside of the rotor in the outer portion of the trough. After welding, Woods metal is poured in and allowed to solidify. The slot is then machined to the desired dimensions followed by melting out the Woods metal, leaving the baffling in place with a continuous annular slot in the portions of the baffling extending away from the

periphery of the trough to enable movement about the vane.

In the modification of the device shown in Figures 7 and 8, separate, arcuate-ended, generally rectangular perforated baffles or inserts 18-18 equidistant from each other and parallel to the radii of the rotor are secured to the rotor in the outer portion of the trough. Each baffle has a slot in which the stator or vane may freely lie, and, thus, the separate baffles carried by the rotor may move about the stator. The results achieved when using a plurality of separate baffles during operation of the device are the same as when the continuous baffling is used.

In securing the individual baffles to the inside of the rotor, grooves 19-19 are cut in the inside walls of the rotor, and the side edges 20-20 of the baffles inserted therein. The baffles may then be welded to the rotor or the metal near the grooves mashed or peened to cause it to close about the baffles. Woods metal is then poured in and the baffle machined as described supra to provide slots of the desired dimensions. The slots, however, can be cut in the baffles prior to insertion in the rotor trough if careful machining techniques are observed.

The baffling material can be of metal or any other material having the requisite strength, capable of being secured to the rotor, and adaptable for use in centrifugal shaft seals. It must be apertured, porous, perforated, etc., in order that the fluid in each pocket can readily contact the fluid in the adjacent pocket and in order that the fluid will be in a somewhat continuous fluid mass to provide the necessary sealing under the action of centrifugal force. Examples of preferable materials are wire screening, perforated metal strips or inserts of heavy stainless steel, nickel, etc.

The mesh size of the baffling, where screening is used, can be of any size or number per linear inch provided that substantial interference at the fringes of the eddy currents is produced, adequate consideration being given to the temperature and viscosity of the fluid and the speed of the rotor in order that the fluid will act as a sealing medium under centrifugal force. Thus, sizes of from 50 to 400 mesh can readily be employed, although with mercury and oils, it is preferred to use mesh sizes of from 100 to 200.

The baffling disclosed herein is particularly useful with centrifugal fluid shaft seals but can be employed with shaft or other similar seals wherein a stationary or relatively stationary annular member contacts or dips into a fluid which is held by a rotating member and which is under the influence of substantially centrifugal force and thereby effects a seal between materials at different pressures. Moreover, this invention is not to be understood as restricted to shaft seals employing only one vane or stator and one rotor but is adaptable for use where a plurality of vanes and/or stators and rotors are used to effect a sealing action whether the rotor, vane, and shaft are independently or dependently driven, whether the vane or shaft is stationary or operational, and whether they are in a vertical or horizontal position or variation thereof. It is apparent to those skilled in the art that the vane or stator, and also the rotor where necessary, should be accurately machined and polished to further reduce any turbulence of the fluid that might be caused by surface irregularities, scale, etc.

Mercury is customarily employed as the sealing

fluid or medium and has been found more desirable when speeds up to 4000 R. P. M. are used in devices employing the present invention. However, it is feasible that many other materials can be used as the sealing fluid. Some examples thereof are glycerine, oil, and water. Moreover, low-melting point metals such as Babbitt, Woods metal, lead and bismuth can be used as the sealing fluid where temperatures are encountered which would cause vaporization of the mercury, oil or water. Molten salts can also be used alone or in combination with some other fluid; for example, tantalum iodide or perfluoride could be used on the top of the mercury where the shaft seal is being used to seal against gases at low temperatures. It is, of course, apparent that some change in dimensions of the parts of the centrifugal shaft seal may be necessitated where different speeds and sealing mediums are used.

Tests were made using a centrifugal shaft seal comprising a stationary vane, a driven rotor, mercury as the sealing fluid, and with and without the baffling of this invention. Without baffling, the lowest absolute pressure obtainable was 5.5 microns, whereas with baffling the seal was able to sustain a pressure of the order of from 0.15 to 0.50 micron absolute pressure. Without baffling at 4000 R. P. M., leakage was 158 cubic inches of atmospheric pressure air per year, while with baffling it was 22 cubic inches of atmospheric pressure air per year.

A shaft seal embodying the present invention will find particular use in sealing against toxic fumes or vapors, in high-vacuum distillation process, in vacuum smelting, in blower shaft seals, etc.

In summary, this invention teaches that the efficiency of a shaft seal can be greatly increased by providing baffling or baffles in the trough of the rotor to reduce the fluid turbulence caused by the fluid moving past the vane. The baffling or baffles provide interconnected pockets where the sealing fluid is partially entrapped although its overall sealing effect under the action of centrifugal force is not adversely affected. In this manner, the fluid in each pocket, due to reaction between it and the stator, develops eddy currents which interfere at the fringes with the eddy currents of the fluid in the adjacent pockets, thereby reducing the turbulence and increasing pressures obtainable with a comparable reduction in leakage.

Having thus described the invention, what is claimed as new and novel and is desired to be secured by Letters Patent is:

1. In a centrifugal fluid shaft seal, the combination of a rotor having sides defining an internal annular chamber, a sealing fluid adapted to be held under pressure in the outer portion of said chamber when said rotor moves, continuous, perforated slotted serpentine baffling secured to said rotor in the outer portion of said chamber, a stator having an annular periphery adapted to contact said fluid when said rotor moves and to extend into the slotted portion of said baffling, said stator and the walls of said chamber defining a plurality of spaced pockets therebetween, said pockets inducing interference at the fringes of the eddy currents of said fluid caused by drag on said fluid by said stator when said rotor and said baffling are moving.

2. In a centrifugal fluid shaft seal, the combination of a rotor having sides defining an internal annular chamber, a sealing fluid adapted

to be held under pressure in the outer portion of said chamber when said rotor operates, continuous perforated serpentine baffling secured to three sides of said rotor in the outer portion of said chamber, slots extending from the free portion of said baffling and adapted to receive the annular peripheral portion of a stator, a stator disposed in said chamber and about which said rotor is designed to move, an annular peripheral portion of said stator adapted to dip into said fluid when said rotor moves and to freely lie in said slots of said baffling, and said baffles, said stator and the walls of said chamber defining a plurality of adjacent interconnected pockets therebetween, said pockets inducing interference at the fringes of the eddy currents of said fluid caused by drag on said fluid by said stator when said rotor and said baffling are moving and thereby reducing the velocity and turbulence of said fluid.

3. In a centrifugal fluid shaft seal, the combination of a rotor having sides defining an internal annular chamber, a sealing fluid adapted to be held under pressure in the outer portion of said chamber when said rotor moves, slotted and perforated baffling secured to said rotor in the outer portion of said chamber, a stator having an annular periphery adapted to contact said fluid when said rotor moves and to extend into the slotted portion of said baffling, said baffling, said stator and the walls of said chamber defining a plurality of spaced pockets for said fluid.

4. In a centrifugal fluid shaft seal, the combination of a rotor having sides defining an internal annular chamber, a sealing fluid adapted to be held under pressure in the outer portion of said chamber when said rotor moves, a plurality of separate, radially disposed, slotted and perforated baffles secured to said rotor in the outer portion of said chamber, a stator having an annular periphery adapted to contact said fluid when said rotor moves and to extend into the slotted portion of said baffles, said baffles, said stator and the walls of said chamber defining a plurality of spaced pockets therebetween.

5. In a centrifugal fluid shaft seal, the combination of a rotor having sides defining an internal annular chamber, a sealing fluid adapted to be held under pressure in the outer portion of said chamber when said rotor moves, slotted and perforated baffling secured to said rotor in the outer portion of said chamber, an annular member having a periphery adapted to contact said fluid when said rotor moves and to extend into the slotted portion of said baffling; said baffling, annular member and the walls of said chamber defining a plurality of spaced pockets therebetween.

6. In a centrifugal fluid shaft seal, the combination defined in claim 5 wherein said annular member is a vane attached to the shaft to be sealed.

7. In a centrifugal fluid shaft seal, the combination of a plurality of rotors each having sides defining internal annular chambers, sealing fluid adapted to be held under pressure in the outer portion of said chambers, when said rotors move, slotted and perforated baffling secured to said rotors in the outer portions of said chambers, a plurality of annular members each having a periphery adapted to extend into the slotted portion of the baffling in the annular chamber of a rotor and to contact said fluid when said rotor moves, said baffling, each of said annular

members and the walls of said chamber defining a plurality of spaced pockets in each rotor.
